UNITED STATES PATENT OFFICE

JAMES H. LUCAS, OF ELMHURST, NEW YORK, ASSIGNOR TO NICHOLS COPPER COMPANY, OF NEW YORK, N. Y., A CORPORATION OF NEW YORK

APPARATUS AND PROCESS FOR TREATING MATERIALS SUCH AS METAL POWDER

Application filed March 10, 1931. Serial No. 521,548.

This invention relates to an apparatus and process for drying and if desired otherwise treating materials such as metal powder.

Metal powders whose properties are injured by oxidation, require careful handling to avoid injury in this way. Heating of metal powder e. g. copper powder to even moderate temperatures, for example 100° C. in the presence of air will result in oxidation, which may injure the electrical and other properties of the powder, particularly where the heating continues for a few minutes. Such powder if made by a wet process must ordinarily be dried in preparing it for sale. Copper powder for example prepared in accordance with my copending application Ser. No. 484,540, filed September 26, 1930, is obtained by electrolyzing a solution of copper sulfate with sulfonic acid under conditions to produce a spongy mass on the rotating cathode. This spongy mass is scraped off and washed away by a stream of electrolyte, which latter is then removed by washing the powder. This wet powder I formerly proposed to dry by a vacuum dryer in accordance with the process described in the copending application of Eugene Fitzpatrick et al. Ser. No. 287,033 filed June 20, 1928. I have found that this process of drying is capable of producing a satisfactory product but the vacuum apparatus employed is expensive to install and requires more labor for operation than necessary. In addition when copper is deposited on rods in a well-known manner, instead of rotating cathodes as I prefer, it is the usual practice to grind and otherwise treat it after drying. This has required a separate grinder or other apparatus. For example for grinding a Raymond mill has been used. Such powder, however, after grinding contains a relatively large percentage of rejects (particles of improper size) and in addition the density of the copper is increased substantially, which for some purposes is a disadvantage.

The principal object of this invention accordingly is to provide an apparatus and process for treating metal powder and particularly copper powder which shall be simple in construction, inexpensive to install and

efficient in its operation, and which may be employed with efficiency and saving of expense, to heat, grind and otherwise treat the powder, if desired, in the same operation.

The invention accordingly comprises the novel apparatus and combinations thereof, as well as the novel processes and steps of processes which may be carried out in such apparatus, specific embodiments of which are described herein by way of example only and in accordance with the manner in which I now prefer to practice the invention.

In carrying out the process of my invention, I take a wet metal powder such as copper powder as produced for example by the invention of my copending application above referred to and place it in a confined space preferably an airtight chamber. The chamber is preferably vented to allow air and steam to be driven off from the inside upon heating. The powder as introduced into the chamber is preferably combined with sufficient water so that oxidation at room temperature of the metal particles is substantially prevented. The chamber with the copper powder therein is then heated to a temperature to form steam and the steam is allowed to drive out the air contained in the chamber. While the heating of the powder is continued an atmosphere substantially free from air is maintained by the steam. The heating is continued until a temperature above the boiling point of water is attained, which will be reached when all of the water has been driven off from the copper powder. Unless a heat-treatment of the copper is desired, the vent is closed when a predetermined temperature above 212° F. is reached, say 240° F., to exclude back-flow of air into the chamber. During the drying the chamber is preferably maintained in rotation to continuously agitate the powder and to accelerate the drying. If desired, by the introduction of steel or other slugs, grinding of the powder as it dries may be carried on. In case it is desired to heat treat the copper after it has been dried, the temperature may be raised to about 400° C. and maintained there for three or four minutes. Under these conditions an annealing effect is obtained and

the copper powder is thereby rendered less brittle. The mobility, that is, the ease of flow when the copper powder is poured for example may be improved also by heat-treatment, for example the copper is heated in the rotating dryer to about 400° C. for ten minutes. During this heating the powder is kept in constant rotation with the steel slugs present which results in changing over the fluffy pine-tree structure of the copper powder produced by the invention of my copending application mentioned, so that the quantity of round or globular particles is increased. At the same time the density of the copper powder as a whole is not greatly increased. In the former process, however, as mentioned above, where the copper powder was produced on rods and then ground in a Raymond mill, the number of round particles produced was increased but also the density of the copper was considerably increased. In addition in grinding with the Raymond mill, quite a high proportion of rejects, that is, copper particles of improper size were formed tending to increase the expense of this process.

After drying, and carrying out one or more of the other steps as indicated above, the copper powder is discharged from the chamber, cooled, sieved if desired and packaged for the market.

An apparatus which I prefer to use in carrying out the process of my invention, is shown in the accompanying drawings forming part of this application in which Fig. 1 is an elevation partly in section of the apparatus. Fig. 2 is a transverse sectional view of the drying cylinder taken on the line 2—2 of Fig. 1 and Fig. 3 is a diagrammatic plan view of the apparatus with the upper hood removed.

Referring now more particularly to the drawings, the numeral 1 designates a firebox built preferably of firebrick or other refractory material, and mounted near the lower portion thereof is an oil burner 2 projecting through the side wall thereof. This oil burner is used as a source of heat for drying or heat-treating copper powder 3 contained in the airtight horizontal metal drying cylinder 4. The cylinder 4 is one of a battery of drying cylinders shown more clearly in Fig. 3 and all heated in the same firebox. A description of one drying cylinder will suffice for all. Each drying cylinder is mounted in the upper portion of the firebox, being supported by a short solid shaft 5 at one end and a short core or hollow shaft 6 at the opposite end. These shafts are in turn supported respectively by bearings 7 and 8 which lie respectively in slots 9 and 10 in the opposite walls of the firebox. The upper end of these slots is open so that the entire drying cylinder when uncoupled, as mentioned be-

low, may be removed from the firebox for discharge of the copper powder.

The shaft 5 has a worm gear 11 fixed to the outer end thereof which is driven by a worm gear mounted on shaft 12 by an outside source of power not shown. The hollow shaft 6 is connected by a packed coupling 13 with a pipe 14 which preferably leads to the electrolyte heater shown in my copending application mentioned above. Located between the packed coupling and the pipe 14 is a thermostatic valve 15 which is of any desired type and which may be set to close at a predetermined temperature. I prefer to set this valve to close at a temperature above the boiling point of water say at about 240° F. The hollow shaft 6, packed coupling 13 and thermostatic valve 15 provide a through passage from the interior of the drying cylinder 4 through the pipe line 14 to allow passage of air and steam from the dryer to the pipe line and away to the electrolyte heater mentioned. The valve may be a motor driven valve of the Arco type with the current to the motor thermostatically controlled by the usual mercoid control. A switch placed in the electric circuit from the mercoid control to the Arco motor valve will open with an arm operating the motor driven valve. The circuit is then to be closed only by manual operation. The electric signal bell can be operated by placing the contacts therefor in a position such that the arm on the Arco motor valve at the time of closing closes the circuit operating the signal valve.

On the interior of the rotating dryer is placed a series of slugs 16 preferably of hard material suitable for grinding, such as steel. Upon rotation of the dryer these slugs grind the copper powder in the manner of a ball mill. The drying cylinder is provided with a hinged door 17 which extends substantially for the length thereof and which is provided with a clamping means comprising a rotatable bolt member 18 which is threaded through a nut 17 mounted on the door and the lower end of which is provided with a lug 20 which passes under a ledge 21 located on the drum at the door opening. Gaskets 22 of heat-resisting material make tight joints between the adjacent faces of the dryer and the faces of the door. When the door of the dryer is open in order to discharge the copper powder the lugs 16 are prevented from discharge with the powder by means of a wide meshed screen 22a placed over the door opening as shown more clearly in Fig. 2, the mesh being sufficiently large to permit the powder to pass freely therethrough but to retain the slugs.

In Fig. 1 I have shown in the lower part of the firebox a car 23 containing a load of copper castings 24 which are in process of cooling and which may be employed to substitute or supplement the heat from the oil

burner if desired. A hood 25 provided with a stack outlet 26 is provided above the dryers to carry off the exhaust heating gases. Lifts 27 consisting of strips of metal attached to the sides of the drying cylinder are employed to raise the material upon rotation of the cylinder and to allow it to drop back to the bottom thereof.

In operating the apparatus the dryer 4 is charged with wet copper powder 3 up to a height below that of the supporting shafts 5 and 6. Steel slugs 16 are placed therein. The door 17 is clamped down to make the dryer substantially airtight and it is then lowered through the slots 9 and 10 to a horizontal position so that the worm wheel 11 is in contact with the worm drive 12. The coupling 13 is then coupled. The oil burner 2 is then set in operation and is supplemented if desired by the heat from the copper castings 24 and rotation of the dryer is commenced. Steam is generated inside the dryer by the heat rising around the rotating cylinder. This steam drives out the air through the hollow shaft 6, coupling 13, thermostatic valve 15 and pipe 14 to the electrolyte heater, and the steam is conducted from the chamber at a rate to maintain an inert atmosphere about the powder until substantially dry. The heating is continued until the thermostatic valve closes to exclude air from the outside from passing into the chamber. This valve may operate a bell or other signal in order to indicate when it is closed at which time the operator will be advised that the powder is dried and a predetermined temperature, e. g. 240° F. has been reached. If a further heat-treatment is desired the heat may be adjusted to give a higher temperature and rotation may be continued for a desired interval. During the rotation the slugs 16 grind the copper powder and this grinding, as indicated above, may be carried out for any desired interval. A check valve or similar valve 15a is preferably placed as shown in the drawings adjoining coupling 13 to prevent air from returning into the drying chamber.

Although I have described the invention as applicable to copper powder, it will be understood that other metallic powders may be employed therein and other inert vaporizable liquids than water may be employed in drying.

The process and apparatus described are simple and efficient in operation, require little attention and have a high daily output. The product resulting may have its characteristics varied as required, that is, it may be more or less brittle and more or less mobile. The product produced has been found to be substantially free from oxygen content, containing about the same or a little less oxygen than produced by the vacuum method mentioned above.

While I have described my improvements in detail and with respect to preferred forms thereof, I do not desire to be limited to such details or forms, since many changes and modifications may be made and the improvements embodied in widely different forms without departing from the spirit and scope of the invention in its broader aspects. Hence I desire to cover all modifications and forms coming within the language or scope of any one or more of the appended claims. What I claim as new and desire to secure by Letters Patent is:—

1. In a drying apparatus in combination a drying chamber for receiving metal powder containing a liquid capable of producing a vapor substantially inert to the powder, means to heat the chamber to produce vapor from the liquid and vapor exit means for said chamber, said chamber being closed except for said exit means, and means to substantially preclude air from the powder upon its becoming substantially dry.

2. In a drying apparatus in combination a drying chamber for receiving metal powder such as copper powder containing a liquid capable of producing a vapor substantially inert to the powder, means to heat the chamber to produce vapor from the liquid, and a conduit to conduct the vapor from the chamber, said chamber being closed except for said conduit and a valve for closing the conduit to prevent the entrance of air therethrough.

3. In a drying apparatus in combination a drying chamber for receiving metal powder containing a liquid capable of producing a vapor substantially inert to the powder, means to heat the chamber to produce vapor from the liquid, and a vapor exit, said chamber being closed except for said exit, and a valve for closing said exit at a predetermined temperature.

4. In a drying apparatus in combination a drying chamber for receiving metal powder containing a liquid capable of producing a vapor substantially inert to the powder, means to heat the chamber to dry the powder and vaporize the liquid and a vapor exit for said chamber, said chamber being closed except for said exit, and a thermostatic valve to close said exit at a temperature somewhat above the boiling point of water and means for moving said drying chamber to remove the dried metal powder therefrom.

5. In an apparatus for removing water from copper powder, in combination, a heating chamber, a source of heat therein, an airtight metal drying cylinder supported in slots in said chamber to permit its removal therefrom, said cylinder being provided with an exit therefrom communicating with a pipe for conducting moisture generated on heating said copper powder, and a thermostatic valve to close said pipe and prevent admis-

sion of air into said cylinder when the temperature of the copper powder has risen somewhat above the boiling point of water.

6. A process for drying metal powder which comprises heating moisture-containing powder in a chamber to a temperature to convert the moisture into vapor, driving out air from the chamber by the vapor and maintaining by the vapor an atmosphere substantially free from air while continuing the heating.

7. A process according to claim 6 in which the heating is continued until the temperature of the powder is above the boiling point of water and thereafter closing the chamber to substantially prevent entrance of air thereto.

8. A process according to claim 6 in which the powder is kept in agitation during the drying.

9. A process according to claim 6 in which after drying copper powder it is subjected to a heat-treatment in such chamber for annealing the powder at a temperature above the boiling point of water.

10. A process for removing water from copper powder which comprises heating the wet powder in a chamber to a temperature to form steam, driving out air from the chamber by the steam, maintaining by the steam an atmosphere substantially free from air while continuing the heating and proceeding with the heating until the temperature is above the boiling point of water and thereafter closing the chamber and then discharging the dried copper powder.

In testimony whereof I have signed my name to this specification.

JAMES H. LUCAS.

CERTIFICATE OF CORRECTION.

Patent No. 1,852,583.

Granted April 5, 1932, to

JAMES H. LUCAS.

It is hereby certified that error appears in the printed specification of the above numbered patent requiring correction as follows: Page 1, line 19, for the word "sulfonic" read sulfuric; page 3, line 46, for "drawings" read drawing; and that the said Letters Patent should be read with these corrections therein that the same may conform to the record of the case in the Patent Office.

Signed and sealed this 7th day of June, A. D. 1932.
